(57) **CLAIM**

The ornamental design for a frontal configuration of a steering wheel, as shown and described.

DESCRIPTION

FIG. 1 is a front view of a frontal configuration of a steering wheel according to our novel design; and,

FIG. 2 is a perspective view of the frontal configuration of a steering wheel according to our novel design.

The broken lines are for illustrative purposes only and form no part of the claimed design. Also enclosed is a photograph of an embodiment of the design.

1 Claim, 2 Drawing Sheets

FIG. 1

FIG. 2
